DESIGN FOR A COMBINED TOP, BACK PANEL, AND CONTROL ACCESSORIES FOR A COOKING RANGE

Lawrence H. Wilson, Detroit, and Edwin A. Rutenber, Greenville, Mich., assignors to Gibson Refrigerator Company, Greenville, Mich., a corporation of Michigan

Application October 19, 1945, Serial No. 123,038

Term of patent 7 years

(Cl. D81—25)

To all whom it may concern:

Be it known that we, Lawrence H. Wilson and Edwin A. Rutenber, citizens of the United States, residing at Detroit, in the county of Wayne, State of Michigan, and Greenville, in the county of Montcalm, State of Michigan, respectively, have invented a new, original, and ornamental Design for a Combined Top, Back Panel and Control Accessories for a Cooking Range, of which the following is a specification, reference being had to the accompanying drawings, forming a part thereof.

In the drawings—

Figure 1 is a perspective view of a combined top, back panel, and control accessories for a cooking range embodying our new design; and

Figure 2 is a side elevational view of the same.

The dominant feature of our design resides in the portion shown in full lines in Figures 1 and

2. The side of the combined top, back panel and control accessories for a cooking range not shown is the same as the side shown. The back of the combined top, back panel and control accessories for a cooking range is plain.

We claim:

The ornamental design for a combined top, back panel, and control accessories for a cooking range, as shown and described.

LAWRENCE H. WILSON.
EDWIN A. RUTENBER.
